(57) **CLAIM**

The ornamental design for an automobile wing, as shown and described.

DESCRIPTION

FIG. 1 is a perspective view of the rear and left sides of the automobile wing of the invention, the right side of the wing being identical to the left side;

FIG. 2 is a top plan view of the automobile wing illustrated in FIG. 1;

FIG. 3 is a side view showing the right side of the automobile wing of the invention, the left side being identical to the right side; and,

FIG. 4 is a front view of the automobile wing illustrated in FIG. 1, FIG. 4 showing both the rearmost surface of the wing and the underside of the wing.

The broken line showing of environment is for illustrative purposes only and forms no part of the claimed design.
